[57] CLAIM

The ornamental design for a translucent interlocking panel member for ceilings or the like, as shown and described.

DESCRIPTION

FIG. 1 is a front plan view of the panel member;
FIG. 2 is a side view taken from the bottom of FIG. 1
and identical to a side view taken from the left side of
FIG. 1;

FIG. 3 is a side view taken from the top of FIG. 1 and
identical to a side view taken from the right side of FIG.
1; and

FIG. 4 is a rear plan view of the panel member shown
in FIG. 1.
